United States Patent Office.

JOHN T. FOSTER, OF JERSEY CITY, NEW JERSEY.

Letters Patent No. 62,951, dated March 19, 1867.

IMPROVEMENT IN PEAT MACHINE.

The Schedule referred to in these Letters Patent and making part of the same.

TO ALL WHOM IT MAY CONCERN:

Be it known that I, JOHN T. FOSTER, of Jersey City, in the county of Hudson, and State of New Jersey, have invented a certain new and useful Improvement in Machines for Grinding, Mixing, and Shaping Peat and other substances, of which the following is a full, clear, and exact description, reference being had to the accompanying drawing, forming part of this specification, and in which—

Figure 1 represents a plan of a mill or machine, constructed according to my improvement.

Figure 2, a side view thereof.

Figure 3, a horizontal section, taken as denoted by the line xx in fig. 2.

Figure 4, an inverted plan in part; and

Figure 5, a transverse vertical section in part.

Like letters indicate corresponding parts throughout the several figures.

My improvement has reference to the manufacture of peat, or other substance or substances capable of being similarly worked, into blocks, for fuel or other purposes, by means of a mill or machine, which operates not only to grind, but to cut and mix, and afterwards to shape and sever, said material into blocks of equal length and similar form and size; and the nature of my invention consists, firstly, in a peculiarly shaped or constructed stirrer, arranged to revolve on a vertical axis within a cylinder or hopper, and revolving continuation cylinder, formed with oblique slots in its periphery; and further consists in a novel combination, with a stirrer or agitator, of concentric obliquely slotted cylinders, for the more effectual cutting, grinding, and mixing of the peat; also in certain novel devices, or combination of devices, for cutting, shaping, and delivering the peat automatically, by the action of the delivery thereof, into blocks of uniform size.

Referring to the accompanying drawing, A is a cylinder, into which the peat, in its original or undressed state, is thrown or fed at the top, that may be made flaring or of hopper form. The inside of this cylinder, which is shown stationary, is provided with any suitable number of pins, a , projecting inwards, and between which curvilinear-shaped vanes or teeth, $b b$, projecting from or connected by boss or drum with a vertical shaft, B, work by the rotation of the latter, which may be effected by bevel-gear $c c'$, through a driving-shaft, C. These vanes or teeth $b b$ present a convex front edge to their line or lines or planes of motion, and are bevelled, or set sloping upwards, from their rear in said direction on their under surfaces, forming a moderately sharp edge in front, and it may be also in their rear. They are dispersed so as to form a consecutive series, in any number, arranged one below the other in spiral directions round the shaft which carries them, so that no two lie one under the other. Thus constructed and arranged, said teeth serve, in conjunction with the pins $a a$, not only to cut and mix the peat, but to urge or press it downwards through the cylinder A into a lower cylinder, D, within which vanes $d d$, connected with the shaft B, work. These vanes are somewhat of the form of the teeth $b b$, presenting a convex front surface to their travel, but more of a convolute shape, and more closely approximating a vertical position, only slightly inclining in a downward direction towards the rear on said surface, and being of the depth, or thereabouts, of the cylinder D, within which they act upon the peat to mix, and to a certain extent press downwardly on it, and to force or urge it through oblique slots $e e$ cut in or arranged round the cylinder D, which is made to revolve in a reverse direction to the vanes $d d$, and the obliquity of the slots in which is that of sloping towards the rear in a downwardly direction relatively to the course of said cylinder's motion. This cylinder D is one of a system of concentric cylinders, of which there may be any number, arranged on and attached so as to move with a revolving table, E, travelling in a reverse direction to and round the shaft B, say by means of bevel-gear $f f'$. F G are two of such outer concentric cylinders, arranged at a moderate distance apart, and formed with similar inclined slots $g g$ to those of the cylinder D, with which F and G revolve. The closeness or frequency of these slots may be varied in the several cylinders. The cylinders D and F are sufficiently close to each other to receive snugly within them a stationary cylinder, H, formed with slots $h h$ round its periphery, preferably of an oblique form, and sloping in a reverse direction to those of the cylinders D and F, whereby the peat, in being forced or pressed through the three interior cylinders D H and F, is more thoroughly ground, cut, and mixed by the action of the cylinders and their slots, while the obliquity of the latter in the cylinders which revolve exerts a constant tendency to keep the peat down and solid. Arranged round the exterior of the outer cylinder G are any number, though one only is shown, of forming tubes I, through which, by the oblique slots in the outer cylinder, the peat is delivered.

These tubes may be of any suitable size and shape, and each one is arranged to operate in connection with internal and external devices, as follows: J is a stationary and preferably pivoted and adjustable director, arranged across the circular channel which separates the two outer cylinders, and in such relation to the tube I as to cut or shave the mass of peat in said channel, and cause it to be forced out through the oblique slots in the outer cylinder into the tube I. It will be seen that, though the speed of the outer revolving cylinder is so much greater than that of the inner one, the action of the peat approximates throughout the several cylinders; thereby keeping it solid, and timing the delivery to the feed of it by the action of the vanes attached to the shaft B, travelling in a reverse direction to the revolving cylinders, and by the intervention of the stationary cylinder between two of the revolving ones. The peat forced into the tube I, and shaped therein, is driven outwards along a pivoted side guide, K, and up against a gauge, L, attached to a lever, i, which has its upper arm pressed inwards by a spring, j, and its lower arm attached by a loose rod, k, to the lower arm of a lever, l, pivoted to a rocking shaft, m, and the upper arm of which forms a stop, which, at intervals, as herein-after described, serves for a striker, n, connected with the revolving table E, to, as it passes it, force to one side and so rock the shaft m. This shaft carries a radial knife, M, which, when worked, moves across the mouth of the forming tube I, to cut the peat forced out against the gauge L. Said knife is connected by a rod, o, to a lever, p, and is thrown back and held back by the action of a spring, q. The side guide K is geared by a pin and obliquely slotted arm with the knife M, so that when the latter moves forward to cut the peat, said guide also moves forward to aid the knife and support the block in its cut, and to deliver it out of the way into or on to a carrier slide, N, which, every time the knife moves forward, is pushed onwards by the action of a spring-pressed dog, r. The cutting action of the knife M is regulated and called into play automatically by the delivery of the peat against the gauge L, which, when forced outwards or backwards by the peat, brings the stop-lever l in such position that the revolving striker n moves it laterally, and with it the rock-shaft m, knife M, side guide K, and carrier slide dog r. Thus the peat is cut into blocks of uniform shape and length, regulated automatically by the delivery of it. After the cut block has been delivered on to the carrier slide, the gauge L returns to its normal position, along with the knife M and side guide K.

What I claim herein as new and useful, and desire to secure by Letters Patent, is—

1. The stirrer or agitator, formed of vanes b b and d d, connected with a revolving shaft, B, and of a convolute shape or character, inclining, as they revolve, to press the material downwards, for operation in combination with a reversely moving cylinder, D, substantially as specified.
2. The combination, with a revolving stirrer or agitator, of reversely operating concentric cylinders, formed with oblique slots in or through their peripheries, for operation in connection with an intermediate stationary slotted cylinder, substantially as specified.
3. The combination, with the obliquely slotted revolving outer cylinders F G, and forming tube I, of the director J, substantially as shown and described.
4. In combination with the forming tube I, the yielding gauge L, operated by the material in its delivery, as described.
5. The combination, with the forming tube I, and yielding gauge L, of the knife M, moved forward to effect the cut by the action of the gauge, through mechanism connecting it with the mill, substantially as herein set forth.
6. The side guide K, in combination with the knife M and gauge L, for operation together, essentially as specified.
